UNITED STATES PATENT OFFICE

2,547,996

PORTABLE X-RAY UNIT

Cormack E. Boucher, Seattle, Wash.

Application June 9, 1948, Serial No. 32,027

16 Claims. (Cl. 250—90)

1

The present invention relates to portable X-ray units and, more particularly, to X-ray units adapted for use in radiographing annular sections of hollow bodies. While not necessarily limited thereto, the X-ray unit is particularly suitable for use in the radiographic inspection of annular welds of pipe lines.

It is a primary object of the present invention to provide a new and improved self-contained X-ray unit which is compact, light in weight, and reliable in operation. More specifically, it is an object to provide an X-ray unit including a transformer and tube mounted within a single housing, the unit being of relatively small size so as to permit its movement through a pipe, and of sturdy construction so as to withstand any ordinary treatment to which it might be subjected in the field.

A further specific object of the invention is to provide a new and improved housing structure for portable X-ray units of the type described.

Another specific object of the invention is to provide a new and improved X-ray tube mounting in a portable unit of the type described.

Additional objects and advantages of the invention will become apparent as the disclosure proceeds while the features of novelty will be pointed out with greater particularity in the appended claims.

In the drawing, Fig. 1 is a longitudinal side elevation illustrating the transformer unit constructed in accordance with one form of the present invention; Fig. 2 is a longitudinal sectional view of the transformer unit shown in Fig. 1; Fig. 3 is an end view taken along the line 3—3 of Fig. 2; Fig. 4 is a sectional view taken along the line 4—4 of Fig. 3; Fig. 5 is a view taken along the line 5—5 of Fig. 2; and Fig. 6 is a plan view of the transformer incorporated in the X-ray unit.

Referring now more particularly to Fig. 1, the X-ray unit of the invention is illustrated as being mounted within a hollow, cylindrical, metal body such as a pipe 10, the X-ray unit in this instance being particularly adapted for radiographic inspection of annular sections of the pipe such as the annular weld 11. In the use of the X-ray unit, a film mounted within a suitable holder 12 is wrapped around the outside of the pipe 10 over the annular weld 11, and the entire weld is radiographed at a single exposure.

The X-ray unit is wholly contained within a metal housing which, in this instance, is shown as being of an elongated, cylindrical configuration and consisting of two recessed parts, 14 and 15, which are provided with cooperating angular

2

flanges 16 and 17, respectively, on their adjacent ends by means of which the two housing parts may be secured together in a gas tight relation. For reasons as will be explained more fully hereinafter, the X-ray unit is adapted to be supported within the metal body 10 in a predetermined aligned relation with respect to the longitudinal axis of the metal body 10. This may be accomplished by supporting the X-ray unit upon a carriage or by providing a plurality of supporting wheels upon both ends of the housing, or by providing a plurality of such supporting wheels upon one end of the housing only, the other end of the unit being supported upon the end of a tractor used in conjunction with the X-ray unit for moving the unit along the pipe line. As shown in the drawing, the X-ray unit is equipped with a plurality of wheels 18 mounted upon the ends of resilient bracket arms 19, the bracket arms 20 being secured directly to the outer side wall of the housing portion 15. The wheel units 18, 19 are readily removable so that they can be replaced by other wheel units to suit the internal diameter of any given pipe. At least three such wheels 25 should be provided in a circumferentially spaced apart relation about the X-ray unit in order that the housing will be accurately positioned in a predetermined aligned relation with respect to the longitudinal axis of the pipe. It will be understood by those skilled in the art that there will be an inherent tendency for the X-ray unit as well as the propelling tractor to rotate to a greater or lesser degree about the axis of the pipe, and the supporting wheels should be so spaced about the housing that the unit, or at least the X-ray tube therein, will be maintained in the predetermined aligned relation with respect to the pipe axis irrespective of rotational movement of the X-ray unit about the pipe axis. The 30 opposite end of the unit is, in this instance, adapted to be supported upon the conduit tractor used in conjunction therewith for propelling the same through the pipe line. As shown in the drawings, the end wall of the unit remote from the supporting wheels 18 is provided with an outwardly extending cylindrical flange 21 adapted for receiving a ring 22. The ring 22 is provided with a plurality of bracket arms 23 joined together at the coupling fixture 24 adapted to be received in cooperating coupling element (not shown) provided on the conduit tractor. The coupling fixture 24 is also aligned with the longitudinal axis of the X-ray unit so that the unit will be supported by fixture 24 and wheels 18 in coaxial alignment with the cylindrical pipe 10.

Referring now more particularly to the longi-

tudinal, sectional view of Fig. 2, a transformer, indicated generally by the core structure 30, is shown mounted within the housing part 14 while an X-ray tube 31 is shown inclosed within the second housing part 15. As illustrated more clearly in the views of Figures 5 and 6, it will be observed that the transformer core 30 is of rectangular configuration having windings 32 and 33 provided upon its opposite end legs. Shields 34 and 35, of suitable insulating material, are provided between the windings 32 and 33 within the window of the core structure for providing adequate insulation strength between the adjacent outer turns of the two windings. The transformer is supported within the housing part 14 by means of a plurality of suitably arranged brackets 36 and 27 secured to the inner wall of the housing and to which the core structure is bolted as illustrated in Fig. 5. Power supply connections to the primary of the transformer windings may be effected through the leads 38 connected to the terminals 39 extending through the side wall of the housing and suitably insulated therefrom. The terminal 40 is for a ground connection to the core of the transformer and, in this instance, the midpoint of the transformer secondary is also grounded. One terminal of the high voltage winding consists of a contact button 41 provided on the outer surface of the winding 32 adjacent the end of the X-ray tube 31 and on the axis of the housing. A filament voltage winding 44 is provided about the winding 33 and is connected in series therewith, the leads 43 being brought out to the filament terminals of the X-ray tube by means of the heavily insulated, high voltage cable 45.

Referring now more particularly to the views of Figs. 2, 3, and 4, the mounting arrangement for the X-ray tube 31 will be more fully described. It is pointed out that the X-ray tube 31 is of a type which is capable of emitting X radiation throughout an angle of 360° about the longitudinal axis of the tube, the angle of spread of radiations being indicated in Fig. 2 by the angle 47. It will be understood by those skilled in the art that in the case of an X-ray tube provided with an anode face sloping at an angle with respect to the perpendicular to the tube axis, the tube must be tilted so that the plane of the anode face coincides with a radial plane of the housing. The X-ray tube as shown in the drawings, however, is provided with an anode face which is perpendicular to the axis of the tube and, accordingly, the tube 31 may be mounted with its longitudinal axis coinciding with the longitudinal axis of the housing.

The supporting means for the X-ray tube 31 comprises a disc 51 of insulating material having a diameter slightly less than the internal diameter of the housing and which disc is resiliently mounted upon bracket arms 52 secured to the inner surface of the end of the housing part 14. As illustrated more clearly in the enlarged detail view of Fig. 4, each of the resilient mounting means for the disc 51 includes a rubber bushing 53 provided with an annular metal flange 54 for mounting the same within cooperating openings provided in the disc 51, the rubber bushing 53 being provided with a metal core 56 through which the bolt 57 is arranged securing the disc onto the end of the bracket arm 52.

A radiator 60 for dissipating the heat from the anode stem of the X-ray tube 31 is centrally mounted upon the disc 51, the radiator 60 being provided with an axial opening for cooperatively

receiving the anode stem 61. Electrical connection is made between the anode stem 61 and the terminal button 41 provided on the outer surface of the transformer winding 32 by means of a contact spring 62 mounted upon the back side of the disc 51, the contact spring 62 being electrically connected to the radiator 60. The free end of the X-ray tube 31 is supported by means of a plurality of bracket arms 65 of insulating material, the ends of the bracket arms 65 being secured to a cap member 66 arranged over the end of the tube 31, the opposite ends of the bracket arms 65 being secured by means of relatively stiff, tension springs 67 to the outer edge portions of the disc 51. With the outer end of the X-ray tube 31 thus supported, damage to the tube which might otherwise result from severe jars given to the housing is minimized.

The high voltage cable 45 is brought through the insulating disc 51 by means of an insulating tube 71 secured to the disc 51 by nut 72. The outer end of the tube 71 terminates before it enters the field of X radiations from the tube 31 and the cable conductors are connected to a pair of electrically conductive ribbons 73 insulated from each other and secured together in any suitable manner, the outer ends of the ribbon conductors 73 being connected to the filament terminals 74 of the X-ray tube.

In order that a minimum of impedance will be offered to the radiations emitted by the tube 31, it is important that at least the annular wall section of the housing portion 15 lying within the field of the radiations around the tube 31 and over the area indicated by the angle 47 be of a material which is relatively permeable to X radiations such as aluminum or magnesium. It is more expedient, however, to make the entire housing part 15 of magnesium. The bracket arms 65 of insulating material are purposely made relatively light and the ribbon conductors 73 are also made of magnesium or some other material relatively permeable to X radiations so that no shadows will be created by the conductors 73 and the supporting arms 65 upon the film wrapped about the wall section of the pipe being radiographed. The use of magnesium for the entire housing is also advantageous in that the total weight of the X-ray unit is thereby reduced to a minimum.

While the housing 14, 15 may be filled with an insulating liquid, it is preferred, in order to keep down the weight of the apparatus, to fill the housing with a gaseous insulating medium under pressure. Numerous insulating gases are available on the market and which are suitable for use in filling the housing. Gas may be introduced into the housing through the valve fitting 81 mounted in the end wall 82 of the housing part 14 and the gas pressure may be observed by means of the indicator 83 also mounted on the end wall 82. Surrounding the gas fittings 81 and 83 is a cylindrical flange 84 secured to the end wall for cooperatively receiving a closure cap 85, the cap 85 being removably secured onto the flange 84 for protecting the fittings 81 and 83 against injury during handling or usage of the X-ray apparatus. The opposite end wall 88 of the housing may be provided with an eye fitting 89 for facilitating the handling of the unit.

It will be observed that the wheel units are mounted upon the housing outside of the field of radiations of the tube 31, and preferably relatively closely adjacent the end of the transformer nearest the tube.

Having described the invention in what is con-

sidered a preferred embodiment thereof, it is desired that it be understood that the specific details shown are merely illustrative and that the invention may be carried out by other means.

I claim:

1. A portable X-ray unit comprising a two-part cylindrical housing, annular flanges on the adjacent ends of said housing parts for securing the same together in a coaxial relation, a transformer mounted in a first of said housing parts, a disc of insulating material resiliently mounted on said first part adjacent the open end thereof and having a diameter less than the internal diameter of said first part, an X-ray tube having an anode stem mounted on said disc coaxially with said housing parts, an anode radiator fixedly secured to the center of said disc and adapted for removably receiving the anode stem of said tube, bracket arms of insulating material secured to the outer edge portions of said disc for supporting the free end of said tube, electrical connection conductors between the terminals of said transformer and the tube terminals, said tube being adapted for emitting penetrative radiations throughout an angle of 360°, the portions of said second housing part, said bracket arms and conductors within the path of said radiations being of a material relatively permeable to said X-radiations.

2. A portable X-ray apparatus particularly adapted for use in radiographing annular welds in cylindrical metal bodies, said apparatus comprising an elongated, hermetically sealed, cylindrical housing, means secured relatively to the outside of said housing for engaging the inner wall of a cylindrical body at circumferentially spaced apart points around said housing for supporting said housing substantially coaxially within said cylindrical body irrespective of rotational movements of said housing about the axes of said housing and said body, a transformer and an X-ray tube mounted within said housing and spaced apart in the axial direction of said housing, said X-ray tube being capable of emitting radiations throughout an angle of 360°, insulating means secured to said housing and operatively engaging and supporting each of the opposite ends of said tube within said housing and in such a position that the field of X-rays emitted by said tube extends at right angles to the axis of said housing throughout an angle of 360° thereabout, at least an annular portion of the housing in the path of said radiations being of a material relatively permeable to X-rays, said transformer being wholly disposed outside of said field of X-rays.

3. A portable X-ray unit comprising an elongated, hermetically sealed, cylindrical housing, a transformer and an X-ray tube mounted within said housing and spaced apart in the axial direction of said housing, said X-ray tube being capable of emitting radiations throughout an angle of 360°, insulating means secured to said housing and operatively engaging and supporting each of the opposite ends of said tube within said housing and in such a position that the field of X-rays emitted by said tube extends at right angles to the axis of said housing throughout an angle of 360° thereabout, at least an annular portion of the housing in the path of said radiations being of a material relatively permeable to X-rays, said transformer being wholly disposed outside of said field of X-rays.

4. A portable X-ray unit particularly adapted for use in radiographing an annular section of a hollow, cylindrical metal body, said unit compris-

ing a cylindrical housing adapted to be supported within said body and coaxially therewith, a transformer mounted in one end of said housing, an X-ray tube mounted in the other end of said housing, a disc of insulating material resiliently mounted in said housing between said transformer and said tube, means securing one end of said tube to the center of said disc with the longitudinal axis of said tube extending coaxially with said housing; bracket arms of insulating material extending from the peripheral edge portions of said disc to the outer free end of said tube, the portion of said housing surrounding said tube being of a material relatively permeable to X-rays.

5. A portable X-ray unit comprising an elongated housing, a transformer mounted in one end of said housing, an X-ray tube mounted in the other end of said housing, a sheet of insulating material extending transversely of said housing between said transformer and said tube, means resiliently supporting said sheet upon said housing, means mounting one end of said tube on said sheet, and a plurality of tension supporting members extending from the outer edge portions of said sheet to the free end of said tube, the end portion of said housing surrounding said tube being of a material relatively permeable to X-rays.

6. A portable X-ray unit particularly adapted for use in radiographing an annular section of a hollow, cylindrical metal body, said unit comprising a cylindrical housing adapted to be supported within said body and coaxially therewith, a transformer mounted in one end of said housing, an X-ray tube mounted in the other end of said housing and adapted for emitting X-rays throughout a 360° angle radially of said housing, an insulating member extending transversely of said housing between said transformer and said tube, said transformer being disposed wholly outside of the radial field of X-rays from said tube, one end of said tube being mounted on said member with the longitudinal axis of said tube extending coaxially with said housing, and insulating supporting means extending between said housing and the opposite end of said tube, at least an annular portion of said housing surrounding said tube being of a material relatively permeable to X-rays.

7. A portable X-ray unit comprising an elongated housing, a transformer unit mounted in said housing, an X-ray tube capable of emitting X-rays throughout an angle of 360° about said housing and mounted in a longitudinally spaced apart relation therewithin with respect to said transformer unit whereby said transformer unit is outside of the field of radiations from said tube, resilient means secured to said housing and resiliently supporting said tube therewithin, and at least a portion of said housing surrounding said tube throughout 360° and within the field of radiations thereof being of a material relatively permeable to X-radiations.

8. A portable X-ray unit particularly adapted for use in radiographing an annular section of a hollow, cylindrical metal body, said unit comprising a cylindrical housing adapted to be supported within said body and coaxially therewith, a transformer mounted in one end of said housing, an X-ray tube mounted in the other end of said housing, said tube being capable of emitting radiations throughout an angle of 360° in the direction radially of said housing, at least an annular portion of said housing surrounding

7
said tube being relatively permeable to X radiations, and a plurality of circumferentially spaced apart roller means secured relatively to said housing for supporting said housing in coaxial alignment with said metal body irrespective of rotational movements of said housing about the body axis said transformer and said roller means being wholly disposed outside of the field of radiations of said tube.

9. A portable X-ray unit particularly adapted for use in radiographing an annular section of a hollow, cylindrical metal body, said unit comprising an elongated housing, a transformer mounted in one end of said housing, an X-ray tube mounted in the other end of said housing, 10 said tube being capable of emitting radiations in a plane radially of the longitudinal axis of said housing throughout an angle of 360° thereabout, at least an annular portion of said housing surrounding said tube being relatively permeable to X radiations, means for supporting the transformer end of said housing upon a conduit tractor and a plurality of circumferentially spaced apart roller supporting means secured to said housing adjacent the opposite end of said transformer, said transformer and said roller means being disposed in the direction longitudinally of said housing outside of the radial field of radiations.

10. A portable X-ray unit comprising a cylindrical housing, said housing including two complementary cylindrical parts detachably secured together end to end in a coaxial hermetically sealed relation, a transformer unit fixedly mounted in one of said housing parts, an X-ray tube capable of emitting X-rays throughout an angle of 360° mounted in the second of said housing parts, said transformer being mounted outside the field of radiations from said tube, resilient means secured to one of said housing parts and resiliently supporting said tube within said second housing part for radiating X-rays throughout an angle of 360° about the axis of said housing, at least an annular portion of said second housing part within the field of said X-ray emission from said tube being of a material readily permeable to X-radiations.

11. A portable X-ray unit particularly adapted for use in radiographing annular sections of hollow, cylindrical metal bodies, said unit comprising an elongated cylindrical housing adapted to be supported within such bodies and coaxially therewith, a transformer unit mounted within said housing, an X-ray tube mounted within said housing for emitting X-rays radially of said cylindrical housing throughout an angle of 360°, support means for said tube extending transversely of said housing between said transformer unit and said tube, said supporting means including means for insulating said tube from said housing, said supporting means also including resilient mounting means for resiliently supporting said tube with respect to said housing, said transformer unit being disposed wholly outside of the radial field of said X-rays, at least the housing portion surrounding said tube and within the radial field of said X-rays being of a material relatively permeable to X-rays.

12. A portable X-ray unit particularly adapted for use in radiographing annular wall sections of a hollow, cylindrical metal body, said unit comprising an elongated housing adapted to be supported within said body, a transformer unit and an X-ray tube mounted in an axially spaced apart relation within said housing, supporting

5 means for said tube extending transversely of said housing, said supporting means including means for insulating said tube from said housing, said supporting means also including resilient mounting means for resiliently supporting said tube with respect to said housing, said X-ray tube being adapted for emitting radiations in a plane at right angles to the longitudinal direction of said housing throughout an angle of 360°, at least the portion of said housing within the field of radiations of said tube adjacent said plane being of a material relatively permeable to X-rays, said transformer being disposed in the direction longitudinally of said housing wholly to one side of said plane of radiations, said housing comprising a pair of complementary separable parts adapted to be hermetically sealed together.

13. A portable X-ray unit comprising an elongated housing including two recessed members, cooperating annular flanges on the adjacent open ends of said members permitting said members to be secured together in a complementary end-to-end, hermetically sealed relation, a transformer mounted within one of said housing members, an X-ray tube, means mounting said X-ray tube adjacent the end of said one housing member in an outwardly projecting relation with respect to the open end of said one housing member, said X-ray tube being enclosed by the second of said housing members, said tube being adapted for emitting radiations throughout a radial angle of 360° about the longitudinal axis of said housing, at least the annular portion of said second housing member within the radial field of said radiations from said tube being of a material relatively permeable to said radiations, electrical conductors extending between said transformer and the terminals of said tube, 30 at least those portions of said conductors passing through the field of said radiations being of a nature relatively permeable to said radiations.

14. A portable X-ray unit particularly adapted for use in radiographing an annular section in 45 a hollow, cylindrical metal body, said unit comprising an elongated housing adapted to be supported within said body in substantial predetermined coaxial alignment with said body, a transformer mounted in one end of said housing, 50 an X-ray tube mounted in the other end of said housing, said tube being adapted for emitting radiations in the direction at right angles with respect to the longitudinal axis of said housing and throughout an angle of 360° thereabout, at least the annular portion of said housing surrounding said tube and within the field of said radiations being permeable to X-radiations, carrying means adapted to engage with the inner walls of said hollow metal body angularly distributed around said housing for supporting said housing within said body whereby said tube is maintained in substantial predetermined position with respect to the axis of said body irrespective of angular rotational movements of said housing about the body axis.

15. A portable X-ray unit including a housing, 60 an X-ray tube including an anode stem enclosed within said housing, said tube being capable of emitting X-rays throughout an angle of 360°, a support of insulating material, an anode radiator secured to said support and adapted for receiving said anode stem, bracket means secured to said support for engaging and supporting the end of said tube opposite said anode stem, resilient 70 means securing said support to said housing, said

bracket means and at least the portion of said housing surrounding said tube and within the field of said X-ray emission being of a material readily permeable to X-rays.

16. A portable X-ray unit including a housing, an X-ray tube enclosed within said housing, said tube being capable of emitting X-rays throughout an angle of 360°, means for supporting said X-ray tube within said housing, said supporting means including insulating means operatively engaging and supporting each of the opposite ends of said tube, said supporting means including resilient mounting means whereby said tube is resiliently supported relative to said housing, at least an annular portion of said housing surrounding said tube throughout 360° and within the field of X-ray emission from said tube being of a material relatively permeable to X-rays.
